UNITED STATES PATENT OFFICE.

SALOMON DAVIDSON, OF NEW YORK, N. Y.

DESIGN FOR A CHAIN-LINK.

SPECIFICATION forming part of Design No. 13,045, dated July 18, 1882.

Application filed May 31, 1882. Term of patent 7 years.

To all whom it may concern:

Be it known that I, SALOMON DAVIDSON, a citizen of the United States, residing at New York, in the county and State of New York, have invented and produced a new and original Design for Chain-Links, of which the following is a specification, reference being had to the accompanying drawings, forming part thereof.

10 This design consists of a "box," so called, having holes in its sides, of angular bands at the opposite ends of the box, and of a filling-piece which is visible through the holes of the box.

15 In the accompanying drawings, Figure 1 shows the design applied to a short link. Fig. 2 shows it applied to a long link. Fig. 3 is a sectional view of one of the links.

Similar letters indicate corresponding parts. The letter A designates the box; B, its holes;

20 C, the bands, and D the filling-piece. The box A is square or polygonal, and the holes B are formed in its sides, one or more to each side. The bands C are at the opposite ends of the box, one at each end, and they are angular

in cross-section, while the filling-piece D is within the box, together with the bands, so that it is visible through the holes of the box. By these characteristic features a novel and distinguishing appearance is imparted to the link.

What I claim as new, and desire to secure by Letters Patent, is—

1. The design for a chain-link, consisting of a box having holes in its sides, and of angular bands at the opposite ends of the box, as shown and described. 35

2. The design for a chain-link, consisting of a box having holes in its sides, of angular bands at the opposite ends of the box, and of a filling-piece within the box, as shown and described. 40

In testimony whereof I have hereunto set my hand and seal in the presence of two subscribing witnesses.

SALOMON DAVIDSON. [L. S.]
